UNITED STATES PATENT OFFICE

137,204

DESIGN FOR A SWIVEL CHAIR

Peter J. Nordby, Marietta, Ohio, assignor to Marietta Chair Company, Marietta, Ohio, a corporation of Ohio

Application September 20, 1943, Serial No. 111,166

Term of patent 7 years

To all whom it may concern:

Be it known that I, Peter J. Nordby, a citizen of the United States, residing at Marietta, in the county of Washington and State of Ohio, have invented a new, original, and ornamental Design for a Swivel Chair, of which the following is a specification, reference being had to the accompanying drawing, forming part thereof.

Fig. 1 is a side elevational view of a swivel chair, showing my design; and

Fig. 2 is a perspective view thereof, as seen when viewed from the bottom thereof.

The dominant feature of my design resides in the portion shown in full lines in the drawing.

I claim:

The ornamental design for a swivel chair, as shown and described.

PETER J. NORDBY.
